BUCKLE LOCK FOR LUGGAGE OR THE LIKE

Charles S. Gehrie, Montclair, N.J., assignor to Skyway Luggage Company, Seattle, Wash., a corporation of Washington

Filed Oct. 31, 1961, Ser. No. 67,319

Term of patent 14 years

(Cl. D50—7)

FIG. 1

FIG. 2

FIG. 4

FIG. 1 is a top plan view of a buckle lock for luggage or the like embodying my new design;

FIG. 2 is a side elevational view of the same;

FIG. 3 is an end view looking toward the right side of FIG. 1; and

FIG. 4 is an end view looking toward the left side of FIG. 1.

I claim:

The ornamental design for a buckle lock for luggage or the like, as shown.
